UNITED STATES PATENT OFFICE.

EDGAR H. BERRY, OF NEW YORK, N. Y.

DESIGN FOR DEMARCATING-BORDER TO BE IMPRESSED ON STATIONERY.

54,366.

Specification for Design.

Patented Feb. 10, 1920.

Application filed July 6, 1917. Serial No. 179,083. Term of patent 14 years.

To all whom it may concern:

Be it known that I, EDGAR H. BERRY, a citizen of the United States, residing at New York, in the county of New York and State of New York, have invented a new, original, and ornamental Design for a Demarcating-Border to be Impressed on Stationery, of which the following is a specification, reference being had to the accompanying drawing, forming part thereof.

The figure shows the demarcating border as it would appear when printed near one

corner of a sheet of paper, the edges of the sheet adjacent to the said corner being indicated by dotted lines.

I claim:—

The ornamental design for a demarcating border to be impressed on stationery as shown.

EDGAR H. BERRY.
